UNITED STATES PATENT OFFICE.

ISAAC FITTS, OF NASHUA, NEW HAMPSHIRE.

SHEARS.

SPECIFICATION forming part of Letters Patent No. 358,548, dated March 1, 1887.

Application filed June 15, 1886. Serial No. 205,258. (No model.)

To all whom it may concern:

Be it known that I, ISAAC FITTS, a citizen of the United States, and residing at Nashua, Hillsborough county, New Hampshire, have 5 invented certain new and useful Improvements in Shears, of which the following is a specification.

In my Patent No. 338,396 I have described and claimed an improved rod-cutter, and my 10 present invention is an improvement on said cutting device; and it consists in providing a pair of shears in connection with the rod-cutter, whereby both the cutter and shears are operated by the same means.

15 Referring to the accompanying drawings, Figure 1 is a side elevation of my improved device. Fig. 2 is the same, showing the parts in a different position; and Fig. 3 is a plan of Fig. 1.

20 While it is not necessary to particularly describe the construction and operation of the rod-cutter, it being fully set forth in my aforesaid patent, it may be stated to consist, essentially, of a base-plate, C, to which is secured a 25 stationary plate, A, provided with holes *x* to receive the rod to be cut, and a pivoted plate or bar, B, which vibrates with its inner face in contact with the adjoining face of plate A, and the edge of the vibrating or cutting plate is 30 preferably provided with cutting-notches *y*. The cutting-plate is supported in a suitable standard, *a'*, by means of a bolt, *e*, passing through the standard and the plate A. The extended end of the cutter-bar B is operated 35 by suitable mechanism, as by an eccentric or cam, *f*, connected to a lever, L, pivoted on a bolt, *e'*, supported in a standard, *a'*, and the plate A.

I provide the stationary plate A with an 40 extension, M, in the form of one blade of the shears, and having its cutting-edge on a line with the inner surface of the plate A, and the other blade of the shears, N, is connected to and forms a part of the vibrating bar B, the 45 cutting-edge being on the lower side and in operative relation to the lower fixed blade. It

will thus be seen that the same bar that forms the rod-cutter also forms the vibrating blade of the shears, and it may be operated by the same means.

The shears thus constructed are very powerful and are easily operated, and the shears may be used in conjunction with the rod-cutter or separately, as desired, and the whole forms a device that is cheap, compact, and effective.

50 What I claim is—

1. A combined rod-cutter and shears consisting of a stationary blade supported on a base-piece and provided with cutting-edges, 60 as described, of a vibrating blade pivoted adjacent to said stationary blade and having cutting-edges on both sides of the pivot-point, and an eccentric-lever for operating the vibrating blade, substantially as and for the purpose set forth.

2. The combination, with a rod-cutter consisting of a stationary plate, a vibrating cutter-bar in contact with the stationary plate, and a pivoted eccentric-lever actuating the 70 cutter-bar, of an extension of the stationary blade forming one portion of the shears, and an extension of the vibrating blade forming the other portion of the shears, substantially as described.

3. A combined rod-cutter and shears, consisting of a perforated stationary plate having a cutting-extension, a vibrating plate having cutting-notches on one side of the pivot and an extended portion on the other side of the 80 pivot forming the vibrating portion of the shears, and an eccentric for operating both the cutter and the shears, substantially as described.

75 In testimony whereof I have signed my name to this specification in the presence of two subscribing witnesses.

ISAAC FITTS.
